WINDOW SASH OPERATING MECHANISM

James W. Signore, Ellicottville, N. Y.

Application July 15, 1950, Serial No. 174,057

4 Claims. (Cl. 268—132)

1

This invention relates generally to windows but more particularly to certain new and useful improvements in the sash operating mechanism therefor.

It has for one of its objects to provide a mechanism of this character which is so designed and constructed as to facilitate the raising and lowering of the sash and which dispenses with the use of the usual cords and weights and locking latches.

Another object of the invention is to provide a sash operating mechanism which is simple and inexpensive in construction and which can be easily installed.

A still further object is to provide latching means governed by the sash operating mechanism for automatically latching the upper sash in a locked position when the lower sash is in its lowered position.

Other features of the invention reside in the construction and arrangement of parts herein-after described and particularly pointed out in the appended claims.

In the accompanying drawings:

Figure 1 is a sectional inside face view of a window frame showing my improved sash operating and latching mechanism. Figure 2 is a sectional side view thereof taken substantially in the plane of line 2—2, Figure 1. Figure 3 is a horizontal section taken on line 3—3, Figure 1.

Similar characters of reference indicate corresponding parts throughout the several views.

By way of example, my sash raising and lowering mechanism has been shown in connection with the lower sash 10 of a window frame 11, while the latching means is operatively associated with the upper sash 12 of the window.

Secured by attaching flanges 13 to opposite sides of the lower sash 10 are depending channel-like bars 14 which are provided with forwardly-facing gear racks 15 extending below the sill 16 of the window frame. A sectional operating shaft 17, 18 is disposed horizontally between and journaled at its ends in the opposite sides of the window frame below the sill and a depending bracket 19 is secured to the latter for supporting the shaft medially thereon. Pinions 20 are fixed on this shaft in meshing engagement with the companion gear racks, so that as the shaft is turned in one direction or the other the sash is accordingly uniformly raised or lowered. It will be noted that each shaft section 17, 18 has a pinion fixed thereto and that the sections are detachably connected by a set screw 21, so that by varying the length of one or both of the shaft-sections

2

the mechanism is readily adaptable to windows of different widths.

For the purpose of actuating the operating-shaft from the inside of the window, a hand crank 5 22 is provided which is mounted on the inner end of a transverse shaft 23 journaled in bearing lugs 24 formed on the bracket 19. A worm 25 fixed on this crank shaft meshes with a worm wheel 26 secured to the operating shaft. Upon turning 10 the crank in one direction or the other, the racks 15 are accordingly propelled upward or downwardly to raise or lower the sash 10 and at the same time effectually retain it in a desired position of adjustment.

15 Attached at its lower end, as indicated at 27, to one of the rack bars 14 and adapted to move therewith relative to the window frame 11 in a corresponding upright slot 28 formed therein, is an upright post 29 for actuating a latching bolt 30 to and from an operative latching position in engagement with the upper sash 12. This bolt is guided for horizontal movement in an opening 31 formed in the window frame and in the closed position of both the upper and lower sash it engages a recess 32 provided in the opposing side edge of the upper sash, as shown by full lines in Figure 1. Pivoted at 33 to a bracket 34 secured to the upright portion of the window frame is a vertically swinging bolt-actuating arm or lever 35 to the lower end of which the bolt 30 is pivotally joined. Adjacent its fulcrum end this actuating arm has a tappet lug 36 projecting therefrom having a slot 37 therein through which the upper end of the post 29 extends. A spring 38 is applied to this bolt between the arm 35 and an abutting shoulder formed in the adjoining portion of the window frame which tends to urge the bolt automatically to its unlatched position as the lower sash is raised. An adjusting stop element or nut 39 on the post above the arm-lug 40 is adapted, during the lowering movement of the lower sash, to abut the top face of the arm-lug and accordingly cause the bolt to be projected into latching engagement with the upper sash, 45 as shown by full lines in such figure. By this construction, when the lower sash is opened by operating the crank 22, the latching bolt 30 is withdrawn from the upper sash to permit it to be opened, if desired. When the lower sash is 50 lowered to its closed position, assuming the upper sash to have been previously closed, the bolt is automatically actuated to latch such upper sash, it being understood that the raising and lowering 55 of the lower sash automatically governs the un-

latching and unlatching movements of the bolt 30.

I claim as my invention:

1. An operating mechanism comprising the combination of a window frame having upper and lower sash guided therein, of a rack bar secured to the lower sash, an operating shaft supported in the window frame and having a pinion thereon meshing with said rack bar, a latching bolt for the upper sash including a spring for normally urging it to its unlatched position, and means releasably connecting said rack bar with said bolt for projecting the latter to its latching position in response to the movement of the lower sash to its closed position, said means being releasable from said bolt when such lower sash is raised to cause the bolt to be spring-urged to its unlatched position.

2. An operating mechanism comprising the combination of a window frame having upper and lower sash guided therein, of a rack bar secured to the lower sash, an operating shaft supported in the window frame and having a pinion thereon meshing with said rack bar, a latching bolt for the upper sash including a spring for normally urging it to its unlatched position, a member connected at its lower end to said rack bar and extending upwardly therefrom within the frame, and an operative connection between the upper end of said member and said bolt for projecting the latter to its latching position in response to the movement of the lower sash to its closed position.

3. An operating mechanism comprising the combination of a window frame having upper and lower sash guided therein, of a rack bar secured to the lower sash, an operating shaft supported in the window frame and having a pinion thereon meshing with said rack bar, a latching bolt for the upper sash including a spring for normally urging it to its unlatched position, a member connected at its lower end to said rack

bar and extending upwardly therefrom within the frame, and a lever fulcrumed on the window frame including an arm operatively connected to said bolt and a tappet lug in operative relation with said rack bar member for actuation thereby to a bolt-latching position in response to the movement of the lower sash to its closed position.

4. An operating mechanism comprising the combination of a window frame having upper and lower sash guided therein, of a rack bar secured to the lower sash, an operating shaft supported in the window frame and having a pinion thereon meshing with said rack bar, a latching bolt for the upper sash including a spring for normally urging it to its unlatched position, a member connected at its lower end to said rack bar and extending upwardly therefrom within the frame and having a stop element thereon adjacent its upper end, and a lever fulcrumed on the window frame including an arm operatively connected to said bolt and a tappet lug having an opening therein through which said rack bar member freely extends and against which lug said stop element is adapted to abut to actuate said lever in a direction to project the bolt to its latching position in response to the movement of the lower sash to its closed position.

JAMES W. SIGNORE.
